DESIGN FOR A DOILY

Robert J. Hutt and George A. Hutt, Brooklyn,
N. Y.

Application February 28, 1938, Serial No. 75,458

Term of patent 3½ years

To all whom it may concern:

Be it known that we, Robert J. Hutt and George A. Hutt, both citizens of the United States, residing at Brooklyn, in the county of Kings and State of New York have invented a new, original, and ornamental Design for Doilies, of which the following is a specification, reference being had to the accompanying drawing, forming part thereof.

The figure is a plan view of a doily, showing our new design, one fourth being in full-line detail and the rest in dotted outline.

We claim:

The ornamental design for a doily, as shown and described.

ROBERT J. HUTT.
GEORGE A. HUTT.
